(57) **CLAIM**

The ornamental design for a can cooler, as shown and described.

DESCRIPTION

FIG. 1 is a top, perspective view showing a first embodiment of a new design for a can cooler.

FIG. 2 is a bottom, perspective view of the can cooler of FIG. 1.

FIG. 3 is a front view of the can cooler of FIG. 1.

FIG. 4 is a back view of the can cooler of FIG. 1.

FIG. 5 is a left side view of the can cooler of FIG. 1.

FIG. 6 is a right side view of the can cooler of FIG. 1.

FIG. 7 is a top view of the can cooler of FIG. 1.

FIG. 8 is a bottom view of the can cooler of FIG. 1.

FIG. 9 is a top, perspective view showing a second embodiment of a can cooler.

FIG. 10 is bottom, perspective view of the can cooler of FIG. 9.

FIG. 11 is a front view of the can cooler of FIG. 9.

FIG. 12 is a back view of the can cooler of FIG. 9.

FIG. 13 is a left side view of the can cooler of FIG. 9.

FIG. 14 is a right side view of the can cooler of FIG. 9.

FIG. 15 is a top view of the can cooler of FIG. 9; and,

FIG. 16 is a bottom view of the can cooler of FIG. 9.

The broken lines are used to show parts of the can cooler which are not being claimed.

1 Claim, 14 Drawing Sheets
